UNITED STATES PATENT OFFICE.

HERMAN F. SCHONEMAN, OF CHICAGO, ILLINOIS.

COMBINATION TOOTHBUSH.

1,420,581.

Specification of Letters Patent. Patented June 20, 1922.

Application filed April 23, 1921. Serial No. 463,916.

To all whom it may concern:

Be it known that I, HERMAN F. SCHONEMAN, a citizen of the United States, residing at Chicago, in the county of Cook and State 5 of Illinois, have invented new and useful Improvements in Combination Tooth-brushes, of which the following is a specification.

This invention relates to a tooth brush 10 construction and has for its primary object to combine a tooth brush and a holder in a very compact novel construction, which will keep the brush in a sanitary condition at all times.

15 An object of the invention is the convenient manner of connecting and assembling the parts so that the device may be readily carried in a pocket or purse.

A feature of my invention is that owing to 20 its compact arrangement of parts the same can be conveniently carried thereby enabling the user to brush his teeth as often as necessary during the day.

Besides the above my invention is distinguished in the use of a removable brush head 25 and an air tight receiver for the dental material.

With these and other objects in view the invention will be better understood from the 30 following detailed description taken in connection with the accompanying drawing wherein:

Fig. 1 is a side elevation of my invention.

Fig. 2 is a longitudinal sectional view with 35 the brush head in one position.

Fig. 3 is a similar view of the brush head in another position.

Fig. 4 is a cross sectional view.

Again referring to the drawing illustrating 40 one of the many constructions of my invention the numeral 1 designates a barrel having one end 2 closed and provided with a vent 3. The other end 4 is open and flared as indicated at 5 so as to have tight frictional engagement with the tapering bottom portion 6 and the receiver 7. This receiver 45 is slightly tapered throughout so that either end may be frictionally engaged by the open end 4 of the barrel. A cap 8 is provided

having screw threaded engagement 9 with 50 the receiver so as to close the same and keep the dental material that is arranged within the receiver in a sanitary condition.

The tapering bottom 6 of the receiver is provided with an extension 10 formed with 55 a dove tail slot 11 slidably receiving the dove tail rib 12 on the brush head 13. From this construction it will be seen that when the bristles become worn the head may be readily disconnected and a new head substituted, thereby enabling the remaining portions of the structure to be used again, therefore, I provide a very inexpensive combined tooth brush and holder.

To complete the invention I secure a clip 60 14 to the barrel so that the device may be carried similar to a fountain pen.

From the foregoing description taken in connection with the accompanying drawing it will be seen that I so shape and construct 70 70 the various parts that a relatively small article is provided which is capable of keeping the brush in a very sanitary condition as well as the dental material. By having the device so compactly arranged the same can 75 be conveniently carried so as to enable the user to brush his teeth often during the day.

It is, of course, to be understood that the various parts may be constructed in various other manners than illustrated, and associated in other relations, and therefore, I do not desire to be limited in any manner except as set forth in the claim hereunto appended.

Having thus described my invention what 85 I claim is:

A combination tooth brush comprising a barrel having one end flared, a double cone shaped receiver adapted to have its ends interchangeably and frictionally engaged in 90 said flared end, a brush head connected to one end of said receiver, and a cap screw threaded to and enclosing the other end of the receiver and conform to the taper thereof. 95

In testimony whereof I affix my signature.

HERMAN F. SCHONEMAN,
